(57) **CLAIM**

The ornamental design for an organizer for athletic gear, as shown and described.

DESCRIPTION

FIG. 1 is a perspective view of an organizer for athletic gear, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken line showing of the hook is for the purpose of illustrating portions of the organizer for athletic gear that form no part of the claimed design.

1 Claim, 4 Drawing Sheets
